ATTORNEYS

UNITED STATES PATENT OFFICE

WILLIAM W. SMALLEY, OF CHICAGO, ILLINOIS.

DRAFT REGULATOR.

Application filed January 11, 1922. Serial No. 528,462.

To all whom it may concern:

Be it known that I, WILLIAM W. SMALLEY, a citizen of the United States, and a resident of Chicago, in the county of Cook and State 5 of Illinois, have invented a new and useful Improvement in Draft Regulators, of which the following is a full, clear, and exact description.

My invention relates to improvements in 10 draft regulators, and it consists in the combinations, constructions, and arrangements herein described and claimed.

An object of my invention is to provide a 15 draft regulator which is automatically controlled and which is adapted to open the draft door and to close the check draft of a furnace.

A further object of my invention is to 20 provide a device of the character described which is simple in construction, and which is not likely to easily get out of order.

Other objects and advantages will appear 25 in the following specification, and the novel features of the invention will be particularly pointed out in the appended claims.

My invention is illustrated in the accompanying drawings, forming part of this application, in which

Figure 1 is a side elevation of the device 30 as shown operatively attached to a draft door and a check draft of a furnace,

Figure 2 is a front elevation of the device,

Figure 3 is a plan view of the device as 35 shown secured to the furnace, and

Figure 4 is a section along the line 4—4 of Figure 2.

In carrying out my invention, I provide 40 an L-shaped arm 1 which is secured to a furnace 2 by means of bolts 3 (see Figure 3). The free end 4 of the arm 1 is curved so as to conform with the under side of an alarm clock 5. The portion 4 of the arm 1 has secured thereto a curved plate 6, the 45 plate having slots 7 therein through which the legs 8 of the alarm clock 5 are adapted to extend. The legs 8 of the alarm clock 5 are threaded so as to receive nuts 9 thereon. With this construction, the clock 5 is 50 rigidly secured to the arm 1. The purpose for providing elongated openings or slots 7 in the plate 6 is, that the plate 6 may re-

ceive any type of alarm clock, since the legs 8 of any alarm clock may be readily received in the slots 7. The clock 5 is provided with 55 the usual time winding and alarm winding stems 10 and 11, respectively.

As clearly shown in Figure 3, the arm 1 carries a rod 12 on which a frame 13 is pivotally mounted. The frame 13 is held in place by means of a nut 14 which is screwed on the free end of the rod 12. The rod 12 has a coil spring 15 wrapped therearound, one end of the spring being disposed under the frame 13 and the other end of the spring 60 being disposed over the arm 1 (see Figure 3). The spring tends to normally swing the frame 13 into the raised position shown in Figure 1. The frame 13 has a ring 16 secured to the upper side thereof and a ring 17 secured to the lower side thereof. A cable 18 is secured to the ring 16 and is passed over pulleys 19 which are carried by brackets 20, the brackets being secured to the sleeve 21 (see Figure 1). The free end 65 of the cable 18 is secured to the check draft 22 of a flue 23. The ring 17 has a cable 24 secured thereto, the cable being connected to a draft door 25. From this construction 70 it will be observed that when the frame 13 is swung from the horizontal position shown in Figure 1 to the raised position, it will automatically open the draft door 25 and at the same time will close the check draft 22.

In Figure 4, I have shown a simple means 75 by which the frame 13 is held in a horizontal position against the tension of the spring 15. This means comprises a bushing 26 which is carried by the arm 1 and in which is rotatably mounted a locking member 27. The locking member has a head 28 integral therewith and is threaded at its free end so as to receive a nut 29 thereon. The head 28 and the nut 29 permit free rotation of the member 27 and prevent any longitudinal 80 movement of the same with respect to the arm 1. The member 27 is further provided with a slot 30 and a bore 31. The frame 13 carries a finger 32 which is adapted to pass through the slot 30 and to be received in 85 the bore 31. When the member 27 is rotated so as to bring the slot 30 into any other position except the position in which the slot is at the top of the member 27, the 90 95 100

member will hold the finger 32 and will prevent the frame 13 from being swung upwardly about the rod 12.

The member 27 is adapted to be actuated by means of the clock 5 so as to automatically release the frame 13 at a predetermined time. An arm 33 is screwed onto the alarm winding stem 11 and is operatively connected by means of a link 35 to an arm 10 34 which is carried by the member 27. When the alarm is actuated, it rotates the stem 11 which swings the arm 33 from the full line position to the dotted line position shown in Figure 2, and will swing the arm 15 34 so as to bring the slot 30 to the top of the member 27, whereby the finger 32 may be swung away from the bore 31 by means of the spring actuated frame 13.

From the foregoing description of the 20 various parts of the device, the operation thereof may be readily understood. The alarm of the clock 5 is set for any predetermined time and the member 27 is disposed so as to retain the finger 32 in the 25 bore 31. When the alarm is set off, it will rotate the arm 33 so as to bring the slot 30 to the upper side of the member 27 as heretofore described. The spring 15 will then swing the frame 13 into the raised position 30 shown in Figure 1, since the finger 32 is now free to pass from the bore 31 and through the slot 30. As the frame 13 is swung upwardly by the spring 15, it will open the draft door 25 and will close the check draft 35 22. The air will now enter the furnace 2 by means of the door 25 and will start the fire burning briskly in the ordinary manner.

It will be seen from the construction 40 shown in Figure 2 that the arm 34 is not as long as the arm 33. When the alarm is actuated, it will swing the arm 34 until the latter is in alinement with the link 35 as shown in the dotted line position of Figure 2. The arm 33 will be prevented from rotating any further and will automatically stop the alarm spring from unwinding. When the arm 34 is in the dotted line position, the slot 30 is disposed at the top 45 50 of the member 27 and permits the finger 32 to be released from the bore 31. In setting the device for the next operation, the frame 13 is swung into a horizontal position so as to permit the finger 32 to pass through the slot 30 and into the bore 31. The arm 34 is then swung from the dotted line position to the full line position of Figure 2 and will in turn swing the arm 33 from the dotted line position to the full line position. The 55 60 65 swinging of the arm 34 to the full line position will swing the slot 30 to the position shown in Figure 4 and will prevent the finger 32 from passing through the slot. It will be noted that the alarm is automatically wound at each setting, and I therefore

provide a simple device in which the clock need never be removed so as to permit the winding of the alarm.

From the foregoing, it will be observed that I have provided a simple device which 70 is efficient for the purpose intended and which is automatic in operation. Furthermore, the device requires very little attention except for the winding of the clock so as to keep the latter running. 75

I claim:

1. A device of the type described comprising an L-shaped bar, a spring-pressed frame pivotally carried by said bar, the free end of said frame adapted to be normally disposed in the bend of said L-shaped member, a sleeve carried by said bar, and having a slot therein, a finger carried by the free end of said frame and adapted to enter said slot and to be received in said sleeve, 80 a clock having an alarm winding stem, and means operatively connecting said stem to said sleeve, whereby the rotation of said sleeve will release said frame.

2. In a device of the type described, a 90 bar, a cylindrical member rotatably mounted in said bar and having a bore therein, said member having a longitudinal slot communicating with said bore, an arm carried by said member, a clock carried by said bar 95 and having an alarm winding stem, a second arm secured to said stem, and a link connecting said first and said second named arms together.

3. In a device of the type described, a 100 bar having a curved portion therein, an arcuate-shaped plate secured to the curved portion of said arm and having circumferentially extending slots therein, a clock having legs adapted to project through said 105 slots, said legs being threaded, and nuts disposed on said legs and being adapted to secure said legs to said plate.

4. In combination with a furnace having a draft door and a check draft, of a bar secured to said furnace, a spring-pressed frame pivotally secured to said bar and having an integral finger, a sleeve rotatably mounted in said bar and having a slot therein adapted to receive said finger, cables 110 115 operatively connecting said draft door and said check draft to said frame, a clock carried by said bar and having an alarm winding stem, and means operatively connecting said stem to said sleeve, whereby rotation of said sleeve will release said frame.

5. In a device of the type described, a bar, a cylindrical member rotatably mounted in said bar and having a bore therein, said member having a longitudinal slot communicating with said bore, an arm carried by said member, a clock carried by said bar and having an alarm winding stem, a second arm secured to said stem, and a link connecting said first and said second named 125 130 arms.

arms together, said second named arm being longer than said first named arm.

6. The combination with a furnace having a draft door and a check draft, of a frame secured to said furnace, means carried by said frame for operating said draft door and said check draft, means adapted to normally lock said door operating means

against movement, a clock, and means operatively connecting the alarm stem of the 10 clock with said locking means, the means connected with the alarm stem of the clock being adapted to lock the stem against rotation after the stem has rotated through a portion of a circle.

WILLIAM W. SMALLEY.
